UNITED STATES PATENT OFFICE.

WILSON W. HARBOURT, OF PEWEE VALLEY, KENTUCKY, ASSIGNOR OF ONE-HALF TO
JAMES L. CAPLINGER, OF PEWEE VALLEY, KENTUCKY.

GAME APPARATUS.

1,190,891.

Specification of Letters Patent. Patented July 11, 1916.

Application filed March 22, 1916. Serial No. 85,911.

To all whom it may concern:

Be it known that I, WILSON W. HARBOURT, a citizen of the United States, residing at Pewee Valley, in the county of Oldham and 5 State of Kentucky, have invented certain new and useful Improvements in Game Apparatus, of which the following is a specification, reference being had to the accompanying drawings.

10 This invention relates to certain improvements in game apparatus and has relation more particularly to an apparatus of this general character wherein a surface projectile is employed, and it is an object of the 15 invention to provide a novel and improved apparatus of this general character wherein a game may be played closely resembling the well known game of baseball.

It is also an object of the invention to provide 20 an apparatus of this general character including novel and improved means whereby a projectile may be impelled in a direction toward a striking member.

The invention also has for an object to 25 provide an apparatus of this general character wherein a novel and improved striking means is employed and adapted to coact with a projectile thrown by the impelling means.

30 Furthermore it is an object of the invention to employ a catching member of novel and improved construction which is adapted to be adjustably supported at a predetermined point relative to the striking member 35 and in a position generally occupied by a player in the game of baseball.

The invention consists in the details of construction and in the combination and arrangement of the several parts of my improved 40 apparatus whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view in top plan of a game apparatus constructed in accordance with an embodiment of my invention; Fig. 2 is 55 an enlarged sectional view taken substan-

tially on the line 2—2 of Fig. 1; Fig. 3 is an enlarged view partly in elevation and partly in section illustrating the striking member or bat as herein included; and Fig. 4 is an enlarged sectional view taken substantially on the line 4—4 of Fig. 1.

As disclosed in the accompanying drawings, 1 denotes a base board provided with the upstanding marginal flanges 2 and depicted on the upper face of the base board 1 is a bird's-eye view of a baseball field, and suitably positioned upon the base 1 are the fielding members C positioned at points generally occupied by the fielding players in a baseball game and directly behind the home plate and at opposite sides thereof are the fielding members C' which serve as the receiving end of a battery, while the fielding members C² are positioned at opposite sides of the pitcher's box whereby fielding means 75 are afforded at the pitcher's station.

As each of the fielding members C, C' and C² are substantially identical in construction, it is thought that a detail description of one will suffice for the purposes of disclosure.

As herein embodied, each of the fielding members consists of an elongated plate having one marginal portion adapted to rest directly upon the upper surface of the base plate 1 and provided with a longitudinally disposed slot 2' through which is loosely directed the threaded shank 3 projecting upwardly from the base plate 1 and with which is engaged the clamping nut 4, whereby it 90 will be perceived that the fielding member may be readily and conveniently adjusted, as the player of the game may deem to be of best advantage. It is to be noted, however, that the fielding members C² are permanently secured in applied position.

The intermediate portion of the plate is formed in the upstanding flanges 5 whereby the opposite marginal portion 6 of the plate is spaced a predetermined distance relative to the upper face of the base plate 1, and it is to be observed that the marginal portion 6 is bowed inwardly in cross section whereby the projectile P may be effectively held thereby.

The projectile P is spherical in form and preferably formed of steel so that it will have sufficient weight as to cause the same, when impelled, to travel directly upon the upper surface of the base board 1 in order 110

to facilitate the projectile P being caught by the various fielding members.

Projecting upwardly from the base board 1 at a predetermined distance at one side and rearwardly of the home plate is the bolt or pin 7 which also passes through the spacing block 8 permanently fixed to the base board 1 and pivotally engaged intermediate its length with said bolt or pin 7 is the 10 striking member or bat 9 of predetermined dimensions and which has its striking end provided with a metallic ferrule 10 for a purpose which is believed to be clearly apparent to those skilled in the art to which 15 my invention appertains.

The bolt or pin 7 preferably consists of a headed member having its head 11 overlying the striking member or bat 9 and having its threaded shank extending through the base 20 board 1 and with which is engaged the holding nut 11. I also find it of advantage to surround the bolt or pin 7 with the washer member 12 interposed between the striking member or bat 9 and the spacing 25 block 8 as is believed to be clearly disclosed in the accompanying drawings.

Secured to the end of the striking member or bat 9 remote from its striking end is the retractile member 14, preferably an 30 elastic band, which is suitably anchored, as at 15, to the base board 1, whereby it will be perceived that after the striking end of the bat or member 9 has been retracted or drawn backwardly, requisite impulse will 35 be imparted thereto when the striking member or bat 9 is released to knock the projectile P across the playing field, and it will be noted that should the projectile, after having been struck by the member or bat 9, be 40 caught by any of the fielding members C, C' or C'', an "out" will be registered. A "fair" ball will be determined in the same manner as in the well known game of baseball and any rules may be adopted which 45 will determine the value of a "hit" or to control the other features of the game.

16 denotes a stop member suitably secured to the base plate 1 and with which the striking end of the member or bat 9 is adapted 50 to contact in order to limit the rearward or retracted position of said member or bat.

The impelling member comprises two elongated parallel members 17 having adjacent extremities connected by the cross bar 55 18, whereby said parallel members 17 are maintained in predetermined spaced relation, and at a point intermediate the parallel members 17, the cross bar 18 is provided with the opening 19 through which 60 the striking arm 20 is loosely directed. The outer end of the striking arm 20 is provided with the cross head 21 and secured to the opposite ends of the cross head 21 are the retractile members 22 which are also secured 65 to the forward ends of the parallel members.

17. It is preferred that the retractile members 22 consist of elastic bands.

The space between the parallel members 17 affords a guide in which the projectile P is initially positioned, and said projectile is 70 adapted to be struck by the striking arm 20 under the influence of the retractile member 22, whereby it will be perceived that the projectile P will be impelled toward the home plate. 75

The impelling member is under control of one player while the striking member or bat is under control of the second player, and it will be perceived that unusual skill may be developed in operating the impelling member and to release the striking member or bat at such a time as to cause the projectile to be knocked into "fair" territory. It is to be noted that the forward ends of the parallel members 17 terminate between the fielding 80 members C' at the rear thereof, and it is also to be noted that the retracting movement of the striking arm 20 is controlled by the stop 23 secured to the base board 1 at a predetermined point rearwardly of the impelling device. 85

I also find it of advantage to provide the rear face of the cross bar 18 with the buffers 24 with which the cross head 21 engages in a manner and for a purpose which is believed to be clearly apparent. 90

It has been found in practice that best results are obtained by having the retractile members 14 and 22 of substantially the same tension. This can be accomplished by 100 turning said retractile members about the set screws 25 which are herein employed as the anchoring means therefor.

From the foregoing description, it is thought to be obvious that an apparatus constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice. 105 110 115 120

I claim:

A game of the character described comprising an impelling mechanism, said impelling mechanism consisting of elongated parallel members, a cross member connecting adjacent ends thereof and maintaining said elongated members in predetermined spaced relation, the space between said members affording a projectile receiving guide, a striking arm slidably disposed through the connecting bar and movable 125 130

between the elongated members, a cross head carried by the outer end of the striking arm, and extending beyond the opposite ends of the cross member, a retractile member secured to each end of the cross head and to the forward end of the adjacent parallel member, and a buffer carried by the cross member and with which the cross head engages under the influence of the retractile means, said striking arm when at the

limit of its movement under the influence of the retractile members terminating inwardly of the forward ends of the parallel members.

In testimony whereof I hereunto affix my ¹⁵ signature in the presence of two witnesses.

WILSON W. HARBOURT.
